UNITED STATES PATENT OFFICE

FRED H. KROGER, OF RIDGEWOOD, NEW JERSEY, ASSIGNOR TO RADIO CORPORATION OF AMERICA, A CORPORATION OF DELAWARE

RADIO RECEIVING APPARATUS

Application filed May 23, 1929. Serial No. 365,275.

Briefly and broadly the present invention relates to means for obtaining signals free from disturbances and more particularly to the elimination of static disturbances in the reception of radio signals.

The difficulties encountered in this connection due to the interposition of static effects on the signal effects in the detecting apparatus are well known, and constitute one of the most serious problems in the reception of signals and especially signals transmitted over long distances as for instance, transoceanic signals. Although the effects of static or atmospheric electricity are readily distinguished, the origin, nature and direction of propagation of the disturbances are not well understood.

It has been found that static or at least some of the most objectionable forms of static act as though they are vertically propagated or as though the axis of propagation is nearly vertical. Thus, it would appear that static disturbances are due to a large extent to the variation of the potential gradient of the atmosphere adjacent the earth. Signal waves, however, are substantially horizontally propagated. The operation of my novel invention relies to some extent on the difference in direction of propagation of signal energy and static energy.

Although my invention is not limited to any explanation of the phenomena, as future discoveries may modify this as indicated above the elimination of static effect on receivers in accordance with my invention appears to be, to a large extent, dependent upon the difference in direction of propagation of the signal and static waves.

In securing the improved results I provide a path near the antenna which is of low impedance to vertically propagated waves, but, of high impedance to horizontally propagated signal waves. Thus, my invention provides a novel means for dissipating the static energy which means at the same time not only insures that signal energy is intercepted by the energy pickup but also that directivity of the aerial system is increased.

The features of the invention which are believed to be novel are set forth with more

particularity in the claims forming a part of this specification. The invention and its application in the art, however, will be more fully set forth as to the requirements of apparatus for accomplishing the improved results, and the theoretical action in connection with the following description when read with the drawing, which illustrates the invention in connection with a particular type of antenna. In the drawing

Figure 1 is a diagrammatic perspective view of a suitable arrangement applied to a long low antenna; and

Figure 2 is a similar view of a modification.

In Figure 1 and also in Figure 2, 1 represents a long low antenna; the length preferably amounting to a considerable fraction of a wave length. The antenna illustrated is open at one end and grounded at the other end.

The antenna is supported by any suitable means such as wooden stakes, (not shown). Suitable receiving and detecting apparatus 2 is variably coupled through inductance 4 to an inductance 3 associated with a receiver 2.

Although for purposes of illustration I have shown the antenna as being inductively coupled to a crystal detector, it will be understood that any known form of coupling may be used, and that any known form of receiver may be used, with or without radio and audio frequency amplifier. Furthermore, it will be understood that the receiver used with my novel aerial may be adapted to receive C. W. as well as modulated wave signals.

The particular arrangement shown in both Figures 1 and 2 for carrying out my invention consists of two rows of conducting stakes 5, embedded or grounded in the earth, one row located on each side of the antenna and preferably parallel therewith. The stakes which may be of iron pipe or wires attached to iron pipes, for example, are substantially vertical and extend some distance above the antenna. In Figure 1 the upper ends of the stakes in each row are connected by means of insulating material 6, such as tarred rope.

In Figure 2 the opposite stakes of the rows are connected by means of conductors 7 lo-

cated above and in a direction transverse to the antenna.

Antenna of the type shown are preferably arranged along a line passing through the station to be received. The reception of signal is substantially unaffected by the stakes as the conductivity in the direction of the signal is still substantially as low as before the interposition of the stakes, and the antenna accordingly is not screened from the signal waves. As regards static or other waves having a considerable vertical component along the axis of propagation, the stakes increase the conductivity in that direction and tend to collect and dissipate the energy of the static waves and shield the antenna from the disturbances. From this explanation it will be seen that my invention interposes a path of good conductivity for static in proximity to the antenna, without substantially affecting conductivity in the direction of signal propagation. The difference of potential between the top of the vertical wires and the bottom will be low, but the difference of potential between the feet of the vertical wires is relatively high with respect to signal waves arriving at the antenna.

It is known that an antenna immersed in sea water to a small depth eliminates considerable static. The improvement has been supposed to be due to the fact that the sea water affords a path of relatively low resistance in a vertical direction, in comparison to the resistance in a horizontal direction. The action of the screen described appears to be somewhat similar to the result obtained by the under water antenna, and in accordance with this explanation the arrangement may be considered as effectively raising the ground above the antenna. As sea water is not always available it is of advantage to be able to artificially duplicate the results obtainable with it.

However, regardless of any explanation which may be given, my invention is adapted to give improved results, and such explanations are given merely for a better understanding of the invention.

Having described my invention what I claim is:

1. In radio receiving apparatus, the combination with an antenna of means for eliminating static disturbances comprising a plurality of upwardly extending physically separate grounded conductors in proximity to the antenna, the upper ends of the different conductors having substantially the same difference of potential as the corresponding lower ends of the different conductors, said conductors being also physically separated from said antenna.

2. In radio receiving apparatus, the combination with an antenna of means for eliminating static disturbances comprising a plu-

rality of upwardly extending physically separate grounded conductors in proximity to the antenna and insulated at the upper ends, said conductors being also physically separated from said antenna.

3. In radio receiving apparatus, the combination with an antenna of means for eliminating static disturbances comprising a plurality of upwardly extending physically separate grounded conductors of low impedance insulated from each other at the upper ends, said conductors being located in proximity to the antenna but physically separated therefrom.

4. In radio receiving apparatus, the combination with a horizontally extending antenna of a plurality of upwardly extending grounded conductors of low impedance in proximity to the antenna, the upper ends of the conductors being insulated from each other.

5. In radio receiving apparatus, the combination with a horizontally extending antenna of a row of upwardly extending grounded conductors on each side of the antenna, the upper ends of the conductors in each row being insulated from the upper ends of other conductors in the same row.

6. In a directive aerial system, the combination with a long low horizontally extending antenna grounded at one end, of a plurality of upwardly extending grounded conductors in proximity to the antenna, the upper ends of the conductors projecting above the antenna and being insulated from each other.

7. In radio receiving apparatus, the combination with a long low antenna grounded at one end and extending horizontally in the direction of desired reception, of a row of vertical grounded conductors on each side of the antenna, the upper ends of the conductors in each row being insulated from the upper ends of conductors in the same row.

8. In radio receiving apparatus, the combination with a horizontally extending antenna of a row of grounded conductors on each side of the antenna, the upper ends of the conductors in each row being insulated from the upper ends of conductors in the same row and the upper ends of substantially opposite conductors in different rows being electrically connected.

9. In radio receiving apparatus, the combination with a horizontally extending antenna of a row of grounded conductors on each side of the antenna, the upper ends of the conductors in each row being physically separated from the upper ends of the conductors in the same row and the upper ends of substantially opposite conductors in different rows being electrically connected.

FRED H. KROGER.
